UNITED STATES PATENT OFFICE.

RICHARD F. DUDLEY, OF DUDLEY, WISCONSIN.

LOG LOADER.

1,409,368.

Specification of Letters Patent. Patented Mar. 14, 1922.

Application filed June 5, 1920. Serial No. 386,903.

To all whom it may concern:

Be it known that I, RICHARD F. DUDLEY, a citizen of the United States of America, residing at Dudley, in the county of Lincoln and State of Wisconsin, have invented certain new and useful Improvements in Log Loaders, of which the following is a specification.

This invention relates to a log loader.

10 The object of the present invention is to provide a simple, practical and efficient log loader of strong and durable construction designed for use in forests where trees are felled and the branches removed therefrom and the logs piled on skidways from which they are loaded on motor trucks or other vehicles by the said log loader.

Another object of the invention is to provide a log loader of this character adapted 20 to be easily manipulated and capable of having the derrick or frame from which hoisting mechanism is suspended racked from one side of a road to the other to enable the log loader to be employed for loading logs 25 from skidways at either side of the said road without the inconvenience of turning the log loader around on the road.

With these and other objects in view, the invention consists in the novel construction, 30 combination and arrangement of parts hereinafter fully described, illustrated in the accompanying drawings and pointed out in the claims hereto appended, it being understood that various changes in the form, 35 proportion and minor details of construction, within the scope of the claims, may be resorted to without departing from the spirit or sacrificing any of the advantages of the invention.

40 In the drawings in which like characters of reference designate corresponding parts in the several figures:

Figure 1 is a side elevation of a log loader constructed in accordance with this 45 invention and shown in position for loading logs on a motor vehicle having a trailer attachment.

Figure 2 is an isometric perspective view of the base of the log loader.

50 Figure 3 is an end elevation of the log loader and the truck.

Figure 4 is an enlarged detail view of the top of the derrick frame.

Figure 5 is an enlarged fragmentary view

of the base illustrating the position of the 55 gears when the loader is in position for loading logs.

Figure 6 is a view of the log loader showing the same braced to enable it to be supported from one skidway or location to another and also illustrating in dotted lines the derrick frame racked to the opposite side of the base.

In the accompanying drawings in which is illustrated the preferred embodiment of 65 the invention I have illustrated a motor vehicle generally indicated by the numeral 1 and having a winch attachment 2 mounted thereon. The winch attachment 2 is connected with the driven shaft of a motor 70 vehicle and a cable 20 for raising the logs is adapted to be wound around the drum of the winch. The log loader is equipped with a base comprising spaced side sills or members 3 and transverse bars or members 4 75 extending across the space between the side sills or members and mounted upon and suitably secured to the same and projecting laterally beyond the said side sills or members as clearly illustrated in Figure 2 of the 80 drawings. The transverse bars or members are provided with rack bars 5 suitably secured to the upper faces of the said bars or members 4 and having extended terminal portions which are curved upwardly and inwardly forming substantially semicircular arms 6 which constitute stops and provide 85 seats for pinions or gears 14 which mesh with the racks of the transverse bars as hereinafter fully explained. The curved arms 90 6 are equipped with pawls or dogs 8 connected by suitable hinge joints 7 with the terminals of the arm 6 and adapted to engage the pinions or gears 14, for locking the same against rotary movement as illustrated 95 in Figure 5 of the drawings.

Mounted on the rack member 5 is the derrick frame 9 composed of oppositely inclined sides or frame members and horizontal connecting braces 11 and 12, the brace 11 100 being located at a point intermediate the ends of the derrick frame and the brace 12 being arranged at the bottom of the derrick frame as clearly illustrated in Figure 1 of the drawings. The shaft 13 extends through 105 the bottom brace 12 and also through the lower ends of the frame members of the derrick frame 9 and the pinions or gears 14

are suitably fixed to the end portions of the shaft 13 which is adapted to rotate to permit the derrick frame to be racked from one side of the base to the other when the base 5 is arranged in a horizontal position as illustrated. The ends of the shaft 13 are square and are adapted to receive suitable means for rotating the shaft for racking the derrick frame along the transverse bars of the base 10 and any suitable means may be employed for this purpose. When the log loader is in working position as illustrated in Figure 3 of the drawings, the base is swung upwardly to an inclined position contiguous to 15 the derrick frame and the gears rest in the curved arm 6 at the bottom of the inclined base, a board 14^a or the like being preferably placed under the derrick frame to prevent the same from sinking into the earth. 20 The pawls of dogs engaging in the pinions or gears 14 will hold the gears against rotation and the base securely in the inclined position shown in Figure 3.

The upper ends of the inclined side members of the derrick frame can be secured together either by means of a ring or by the cap piece 10 as shown, the pivot 10^a projecting upwardly longitudinally of the derrick frame and receiving a collar 15 of an approximate L-shaped bracket 15^a extending outwardly and downwardly from the said pivot and having a sheave 16 pivotally suspended from it by a suitable hanger 16^a. The bracket is free to swivel on the pivot 25 10^a which also has mounted on it a collar 17^a of a hanger cable attaching member 17 located above and resting upon the collar 15 and adapted to swivel on the said pivot 10^a. Hanger cables 18 forming guys are secured 30 at their upper ends to the member 17 and are designed to be secured at their lower ends to a tree or otherwise anchored in the ground. The retaining collar 19 is suitably secured to the upper end of the pivot 10^a 40 for retaining the collars 15 and 17^a thereon.

The cable 20 which is wound around the winch of the drum extends upwardly therefrom to the sheave 16 and is arranged thereon and it extends downwardly therefrom and 50 is equipped with a suitable lower cabling device 20^a which may consist of branch cables provided with terminal hooks 21 for engaging the ends of a log as illustrated in Figure 1 of the drawings. The cable 20 is adapted to be wound around the drum of the winch for sliding the logs upwardly 55 along an inclined skidway 22 and thence onto the truck, the loading device enabling the logs to be readily lifted and swung to 60 the proper position on the truck for loading the same.

When the log loader is transported from one location to another, the base is arranged in a horizontal position and the derrick 65 frame is rigidly connected with the base by

means of an inclined brace, the derrick frame extending upwardly at an inclination from one side of the base and the brace extends upwardly at an inclination from the opposite side of the base. The brace is composed of the two bars or members 23 having overlapping intermediate portions and provided at their terminals with suitable keepers 24 of rectangular form and having base members arranged within them as clearly 70 shown in Figure 6 of the drawings. The brace bars or members are secured together and held against relative longitudinal movement by a bolt 25 and the lower end of the brace is secured by a bolt 26 to an ear 27 of the adjacent sill side member 3. The upper end of the brace is suitably secured at 28 to the brace 11 or other suitable fastening device on the derrick frame. Each of the sills or side members 3 of the base is 75 preferably provided with an ear or attaching member 27 to enable the derrick frame to be placed at either side of the base. The ends of the sills or side members 3 are preferably beveled at the lower faces at 29 80 to enable them to constitute runners to permit the loader to be readily moved over the ground from one location to another. In practise one man usually walks on either side of the log loader holding the hanger 95 cables 18 for steadyng the structure while the same is being transported.

What is claimed is:

1. A log loader including a base and an inclined derrick frame extending upwardly 100 at an inclination from the side of the base, said frame being shiftable laterally to either side of the base to enable logs to be loaded at either side of a roadway without moving the log loader.

2. A log loader including a base, and an inclined derrick frame extending upwardly at an inclination from the side of the base and shiftable laterally to either side of the same to enable logs to be loaded at either side of a roadway without moving the log loader, said base being provided with means for permitting it to be swung upwardly contiguous to the derrick frame to arrange the log loader for operation.

3. A log loader including a substantially rectangular base and an inclined derrick frame mounted on the base and means including a rack and pinion for laterally shifting the derrick frame from one side of the base to the other to enable the derrick frame to extend upwardly at an inclination from either side of the said base, and means whereby the base is swung upwardly contiguous to the frame, whereby the log loader is adapted 120 to load logs from either side of the road 125 without moving the log loader.

4. A log loader including a substantially rectangular base provided at opposite sides with curved members forming seats and hav- 130

ing a rack extending across it between the seats, an inclined derrick frame mounted on the base and provided with a pinion meshing with the said rack, said derrick frame being adapted to be shifted along the rack from one side of the base to the other and the base being adapted to be swung upwardly contiguous to the derrick frame to permit the pinion to rest in one of the said curved members for arranging the log loader for operation.

5. A log loader including a substantially rectangular base provided at opposite sides with curved members forming seats and having a rack extending across it between the seats, an inclined derrick frame mounted on the base and provided with a pinion meshing with the said rack, said derrick frame being adapted to be shifted along the rack from one side of the base to the other and the base being adapted to be swung upwardly contiguous to the derrick frame to permit the pinion to rest in one of the said curved members for arranging the log loader for operation and pawls or dogs pivoted to the terminals of the curved members and arranged to engage the pinions for holding the base in an inclined position.

20 6. A log loader including a substantially rectangular base provided with rack bars extending across the base and having curved terminal arms forming seats, an inclined derrick frame adapted to extend upwardly from either side of the base, a shaft mounted on the derrick frame and pinions mounted on the shaft and meshing with the rack bars and adapted to enable the derrick frame to be racked from one side of the base to the other, said base being adapted to be swung upwardly contiguous to the derrick frame and the pinions being adapted to rest in the seats of the curved arms of the rack bars, and pawls or dogs hinged to the terminals of the said arms and arranged to assist in raising the base when being set up.

25 7. A log loader including a substantially rectangular base provided with rack bars extending across the base and having curved terminal arms forming seats, an inclined derrick frame adapted to extend upwardly from either side of the base, a shaft mounted on the derrick frame and pinions mounted on the shaft and meshing with the rack bars and adapted to enable the derrick frame to be racked from one side of the base to the other, said base being adapted to be swung upwardly contiguous to the derrick frame and the pinions being adapted to rest in the seats of the curved arms of the rack bars, and pawls or dogs hinged to the terminals of the said arms and arranged to assist in raising the base when being set up.

30 8. A log loader including a base, an inclined derrick frame, means for shifting the derrick frame laterally to either side of the base and an adjustable brace inclined in the opposite direction to the derrick frame and having means for securing it to the base and to the said frame when the derrick frame is at either side of the said base.

35 9. A log loader including a base having runners and provided with transverse bars connecting the runners and an inclined derrick frame mounted on the base and shiftable to either side thereof, said base being adapted to be swung upwardly contiguous to the derrick frame for arranging the log loader for operation and means for retaining the derrick frame in a horizontal position in rigid relation with the derrick frame to arrange the log loader for transportation.

40

the seats of the curved arms of the rack bars.

7. A log loader including a substantially rectangular base provided with rack bars extending across the base and having curved terminal arms forming seats, an inclined derrick frame adapted to extend upwardly from either side of the base, a shaft mounted on the derrick frame and pinions mounted on the shaft and meshing with the rack bars and adapted to enable the derrick frame to be racked from one side of the base to the other, said base being adapted to be swung upwardly contiguous to the derrick frame and the pinions being adapted to rest in the seats of the curved arms of the rack bars, and pawls or dogs hinged to the terminals of the said arms and arranged to assist in raising the base when being set up.

8. A log loader including a base, an inclined derrick frame, means for shifting the derrick frame laterally to either side of the base and an adjustable brace inclined in the opposite direction to the derrick frame and having means for securing it to the base and to the said frame when the derrick frame is at either side of the said base.

9. A log loader including a base having runners and provided with transverse bars connecting the runners and an inclined derrick frame mounted on the base and shiftable to either side thereof, said base being adapted to be swung upwardly contiguous to the derrick frame for arranging the log loader for operation and means for retaining the derrick frame in a horizontal position in rigid relation with the derrick frame to arrange the log loader for transportation.

In testimony whereof I affix my signature.
RICHARD F. DUDLEY.
